UNITED STATES PATENT OFFICE.

GEORGE L. SMITH, OF BAYONNE, NEW JERSEY.

DESIGN FOR A PUZZLE BOX OR CASE.

SPECIFICATION forming part of Design No. 27,592, dated August 31, 1897.

Application filed July 3, 1897. Serial No. 643,465. Term of patent 3½ years.

To all whom it may concern:

Be it known that I, GEORGE L. SMITH, a citizen of the United States, residing at Bayonne, in the county of Hudson and State of New Jersey, have invented and produced a new and original Design for Puzzle Boxes or Cases, of which the following is a full, clear, and exact specification, reference being had to the accompanying drawings, forming a part thereof.

In the drawings forming part of this specification, Figure 1 is a plan view of my puzzle box or case, and Fig. 2 a central transverse section on the line 2-2.

As shown in the drawings, the leading feature of my design consists of a bottom A, which is circular in form and the central portion of which is convexo-concave, and around the central portion is formed a flat rim a , at the perimeter of which is a circular vertical wall a^2 . Mounted on and secured to the central portion of the bottom, within the circular vertical wall a^2 , is a circular casing composed of a circular top B and a depending annular

rim or flange b , which rests upon the bottom A, and in which are formed a plurality of side openings b^2 , and between the central circular casing is an annular space C, the bottom of which is inclined from said central circular casing outwardly and downwardly, as clearly shown in Fig. 2.

My puzzle box or case is symmetrical in form, and the entire bottom portion or upper surface thereof is plain and smooth, and said design may be of any desired material.

Having fully described my invention, I claim as new and desire to secure by Letters Patent—

The design for a puzzle box or case herein shown and described.

In testimony that I claim the foregoing as my invention I have signed my name, in presence of the subscribing witnesses, this 1st day of July, 1897.

GEORGE L. SMITH.
